PASSAGEWAY T FOR AN ANIMAL HABITAT OR SIMILAR ARTICLE

Allan H. Willinger, New Rochelle, and Albert J. Dinnerstein, Brooklyn, N.Y., assignors to Metaframe Corporation, Maywood, N.J.

Filed July 24, 1972, Ser. No. 274,679

Term of patent 14 years

Int. Cl. D30—07

U.S. Cl. D30—42

FIG. 1.

FIG. 2.

FIG. 3.

FIG. 4.

FIG. 5.

FIG. 1 is a side elevational view of a passageway T for an animal habitat or similar article, showing my new design, the opposite side being substantially a mirror image thereof;

FIG. 2 is an end elevational view, the opposite end being substantially a mirror image thereof;

FIG. 3 is a top plan view;

FIG. 4 is an exploded end elevational view; and

FIG. 5 is an interior side elevational view of one of the halves from which the T is assembled, the interior of the opposite half being substantially a mirror image thereof.

The drawing figures are diagonally lined to indicate transparency.

We claim:

The ornamental design for a passageway T for an animal habitat or similar article, as shown and described.
